CLAIM

The ornamental design for a connector, as shown and described.

DESCRIPTION

FIG. 1 is an isometric view of a connector showing my new design.

FIG. 2 is a front view thereof.

FIG. 3 is a top view thereof.

FIG. 4 is a right side plan view thereof.

FIG. 5 is a left side view thereof.

FIG. 6 is a rear view thereof.

FIG. 7 is a bottom view thereof.

FIG. 8 is an isometric view of a second embodiment of a connector showing my new design.

FIG. 9 is a front view thereof.

FIG. 10 is a top view thereof.

FIG. 11 is a left side view thereof.

FIG. 12 is a right side view thereof.

FIG. 13 is a rear view thereof; and,

FIG. 14 is a bottom view thereof.

The broken lines are for illustrative purposes only and form no part of the claimed design.
